UNITED STATES PATENT OFFICE.

JOHN N. STONG, OF WOODBRIDGE, CANADA.

GRAVITATING DOOR-CLOSER.

SPECIFICATION forming part of Letters Patent No. 448,556, dated March 17, 1891.

Application filed December 11, 1890. Serial No. 374,336. (No model.)

To all whom it may concern:

Be it known that I, JOHN NOAH STONG, farmer, of the village of Woodbridge, in the county of York, in the Province of Ontario, 5 Canada, have invented a certain new and Improved Device for Closing a Door, of which the following is a specification.

The object of the invention is to design a simple device easily attached to any door or 10 gate and which when applied will operate with ease and certainty; and it consists, essentially, of two bars connected together by a knife-joint, the end of one bar fitting into a socket fixed to the door or gate and the end 15 of the other bar fitting into a socket pivoted in a bracket connected to the door-jamb, substantially as hereinafter more particularly explained, and then definitely claimed.

Figure 1 is a perspective view showing the 20 application of my device to a door. Fig. 2 is an enlarged detail of the operating-bars hinged together. Fig. 3 is an enlarged detail of the bracket. Fig. 4 is an enlarged detail of the socket. Fig. 5 is a plan of the 25 joint.

In the drawings, like letters of reference indicate corresponding parts in the different figures.

A and B are two bars connected together 30 by the pin C, and shaped, as indicated in Fig. 2, so as to form what is commonly known as a "knife-joint," the said joint being set so that end pressure against the bars A and B will cause the said joint to operate.

D is a weight supported by the pin C and having a vertical pin E extending from it, and on which an additional weight may readily be placed.

F is a socket fixed to the door G and 35 designed to receive the end of the bar A, as indicated in Fig. 1.

H is a bracket fixed to the door-jamb I and having a socket J pivoted on its end, as clearly shown in Fig. 3. This socket is 40 designed to receive the end of the bar B, as shown in Fig. 1.

The weight D is intended to be heavy 45 enough to hold the bars A and B in the position indicated in Fig. 1, in which position the door is held closed, as shown. When the

door G is open, the end pressure against the bars A and B causes the joint to fold upwardly, and simultaneously the socket J revolves on its pivot, thus permitting the free opening of the door. When the opening- 55 pressure is removed from the door, the weight D forces down the jointed ends of the bars A B, thus causing the door to swing back on its hinges and close.

It will be observed that the bottom end of 50 the socket J is beveled and that it rests upon a correspondingly-beveled surface formed around its pivot on the bracket H. These beveled surfaces are arranged so that the socket J will run, as it were, "downhill" during the closing of the door, and thus render 65 the closing much more easy than were the surfaces perfectly horizontal.

I do not confine myself to the style of weight shown in the drawings, as this may be 70 altered without in any way affecting the principle of the invention; nor do I limit myself to any particular kind or material, shape, or proportions of the various parts of my device.

What I claim as my invention is—

1. Two bars A B, jointed together, the end 75 of one end bar fitting into a socket F, fixed to a door or gate and the end of the other bar fitted into a socket J, pivoted in the end of a 80 bracket H, fixed to the door-jamb in line with the socket F, in combination with a weight applied to the said bar or bars, substantially as and for the purpose specified.

2. Two bars jointed together, the end of one 85 bar fitting into a socket fixed to a door or gate and the end of the other bar fitted into a socket pivoted on the end of a bracket fixed to the door-jamb, the bottom of the said 90 socket being beveled and designed to rest upon a correspondingly-beveled surface formed around its pivot in the said bracket, in combination with a weight applied to the said bar or bars, substantially as and for the purpose specified.

Toronto, November 13, 1890.

JOHN N. STONG.

In presence of—

CHARLES C. BALDWIN,
JOHN E. CAMERON.
